UNITED STATES PATENT OFFICE

WALTER M. AUSTIN, OF PITTSBURGH, PENNSYLVANIA, ASSIGNOR TO WESTINGHOUSE ELECTRIC & MANUFACTURING COMPANY, A CORPORATION OF PENNSYLVANIA

ARC EXTINGUISHING STRUCTURE

Application filed February 9, 1932. Serial No. 591,798.

My invention relates generally to circuit breakers and more particularly to devices for extinguishing large-current arcs in air or gas.

5 The arc-extinguisher of my invention is of the spaced-plate type, in which an arc is drawn and moved into a converging slot that leads to a deionizing chamber having a plurality of spaced conducting or deionizing plates which sub-divide the arc into a plurality of short arcs. The short arcs, under the influence of the flux of a radial field, rotate at a very high velocity between the conducting plates until they become extinct. 10

15 My invention is a further improvement of circuit breakers of the type disclosed in Patent No. 1,784,760, issued to Joseph Slepian, December 9, 1930, and certain subject matter described herein is claimed in the applications for Letters Patent, Serial No. 510,981, filed January 24, 1931, by Frederick B. Johnson, and Serial No. 511,010, filed January 24, 1931, by Robert C. Dickinson, all of which are assigned to the assignee of the 25 present invention.

An object of my invention is the provision of an arc extinguishing device that shall be simple and reliable in operation and be readily and economically manufactured and installed.

Another object of my invention is to provide a deionizing structure having a stack of plates open at both the top and the bottom, so that a direct vent is provided for 30 ventilating the short arcs.

A further object of my invention is to provide a direct vent for each of the short arcs and, at the same time, prevent the arcs from passing through the vents.

40 It is also an object of my invention to prevent the building-up of gas pressure in advance of the arc as it moves into the spaces between the deionizing plates, so that a relatively weak blow-in field, without the provision of heavy multi-turn blow-in coils, is sufficient to move the arc in the said spaces.

Another object of my invention is to provide a ventilating passage having a width substantially the same as the width of the deionizing plates, so that the heat generated

by the arcs may be directly ventilated to the atmosphere.

Another object of my invention is to provide a plurality of deionizing plates, each of which being surrounded by a complementary magnetic plate of approximately the same thickness and substantially in the same plane therewith. 55

Other objects of the invention will hereinafter become apparent. 60

For a fuller understanding of the nature and objects of my invention, reference may be had to the following detailed description taken in connection with the accompanying drawings, showing the preferred embodiment of my invention, in which:

Fig. 1 is a view in elevation of my deionizing structure;

Fig. 2 is a vertical cross-sectional view of my deionizing structure taken along the line II-II of Fig. 3, and illustrating the contact members of a switch associated therewith;

Fig. 3 is a vertical view, in section, of my deionizing structure taken along the line III-III of Fig. 2; 75

Fig. 4 is a vertical cross-sectional view of my deionizing structure, taken along the line IV-IV of Fig. 2; and

Fig. 5 is an exploded perspective view of my deionizing structure. In view of the lack of sufficient length to show the exploded structure, the various parts are shown in two horizontal lines. The parts shown in the lower horizontal line are to be considered as disposed to the left of the parts shown in the top horizontal line, so that, when the members are assembled they will constitute the complete assemblage of my deionizing structure. However, in this view, I have omitted a number of the centrally disposed parts, since they are merely a duplication of the centrally disposed parts shown. 85

Inasmuch as the construction of operating mechanisms of circuit breakers is well known in the art, together with the fact that it constitutes no part of my invention, I have illustrated only the contact members thereof in association with my deionizing structure. As illustrated, my deionizing structure is mounted directly above the contacts of the 90 95

circuit breaker so that the arc may be immediately moved into the deionizing chamber and there extinguished.

As shown in Fig. 2, the reference characters 14 and 16 represent, respectively, the movable and the stationary main contacts of a circuit breaker connected to interrupt the large current power lines 10 and 11. Associated with, and electrically connected to, the 10 movable contact 14 is an arcing contact member 15 resting against the stationary arcing contact member 52 of my deionizing structure, and which opens later than main contacts 14 and 16. This construction is in accordance with the general features of a circuit breaker that is utilized in interrupting high-voltage, large-current circuits, the circuit being finally interrupted at the arcing contacts 15 and 52 to prevent burning of 20 the main contacts 14 and 16. The operating lever and the toggle arrangements, which are generally utilized for operating the main contacts of a circuit breaker, are not shown in the accompanying drawings, as they constitute no part of my present invention.

Referring more particularly to the drawings, my invention comprises generally a plurality of conducting or deionizing plates 27 and 30, each of which is surrounded by 30 a complementary magnetic plate 36 disposed in substantially the same plane therewith, a plurality of insulating members 33, 34, and 35 which separate the conducting and their complementary magnetic plates in order to provide direct ventilating passages for 35 the short arcs, and two convolute coils 54 and 70 disposed respectively on each side of the plates. A bolt 23 extending through the central portion of the plates, in conjunction 40 with the two iron end plates 21 and 22, is utilized for holding the deionizing structure into a unitary device. Preferably, the conducting or deionizing plates 27 and 30 are constructed of copper and the magnetic 45 plates of iron.

As shown best in Fig. 5, the assemblage of a copper conducting plate 27 or 30 within an iron plate 36 constitutes a unitary or composite member of my deionizing arc-extinguisher, and will hereinafter be referred to as a composite plate.

The lower part of the copper conducting plates 30 have a V-shaped portion 37 removed, which, when the plates are stacked, 55 constitutes the apex portion of the converging slot that directs the arc into the spaces between the said conducting plates, while the copper conducting plates 27 that are disposed at each end of the stack of plates 30 60 have no portion of their lower part removed. Therefore, when the conducting plates 27 and 30 are assembled and spaced in a unitary deionizing structure, the lower part of the copper conducting plates 27 constitutes sides 65 of the apex of the entrance slot formed by

the V-shaped slots 37 of the conducting plates 30.

Although I have shown five of the conducting plates 30 in the present embodiment of my invention, it is to be understood that 70 I do not intend to confine myself to this number because the number depends upon the voltage and the current of the power circuit to be interrupted. Generally, the number of plates can be determined by dividing 75 the voltage of the power circuit by 150, which represents the r. m. s. cathode voltage drop between the respective conducting plates at the instant of zero current.

The central lower part of the iron magnetic 80 plates 36 are cut away to form the lower or base portion of the converging slot, which meets the apex portion of the said slot formed by the copper conducting plates 30. In other words, a continuous, converging entrance slot 85 is formed by the portions removed from the iron and copper plates. In this manner, the arc incident to the interruption of a large current circuit is moved into and concentrated at the apex of the slot just before 90 the arc is sub-divided into a plurality of short arcs. As shown best in Fig. 3, the apex of the converging slot extends well into the copper plates so that the radial field flux produced by the coils 54 and 70 aids in transferring the arc between the copper plates. The edges of the converging slot formed by the iron plates 36, when assembled, are protected from the intense heat of the arc, and are also electrically insulated therefrom, by adjacent 95 100 105 110 the V-shaped slots 37 of the conducting plates 30.

Although I have shown five of the conducting plates 30 in the present embodiment of my invention, it is to be understood that 70 I do not intend to confine myself to this number because the number depends upon the voltage and the current of the power circuit to be interrupted. Generally, the number of plates can be determined by dividing 75 the voltage of the power circuit by 150, which represents the r. m. s. cathode voltage drop between the respective conducting plates at the instant of zero current.

The central lower part of the iron magnetic 80 plates 36 are cut away to form the lower or base portion of the converging slot, which meets the apex portion of the said slot formed by the copper conducting plates 30. In other words, a continuous, converging entrance slot 85 is formed by the portions removed from the iron and copper plates. In this manner, the

arc incident to the interruption of a large current circuit is moved into and concentrated at the apex of the slot just before 90 the arc is sub-divided into a plurality of short arcs. As

are cut on opposite sides of each of the alternate copper conducting plates so that when the plates are stacked there is no possible chance for the short arcs to pass through them 5 in series.

The copper conducting plates and their complementary iron plates, when assembled into a unitary structure, are separated by the insulating members 33, 34, and 35. The insulating member 33 is substantially co-extensive with the iron plates, but its central opening is somewhat smaller than the central opening of the iron plates so that it overlaps the copper conducting plates to prevent the 10 short arcs from passing through the narrow space where the copper and the iron plates meet in edge-to-edge relation. (See Fig. 3.) The broken line 90, in Fig. 3, represents the boundary of the copper plates whereas the 15 line 95 represents the edge of the central opening of the insulating member 33. The central opening of the insulating member 33 is substantially round, except for that part where the arc enters tangentially thereto, so that 20 the short arc, under the action of the flux of the convolute coils 54 and 70, may trace recurrent paths between the copper plates until 25 they become extinct.

The insulating members 34 and 35 are disposed along opposite sides of the iron plates 30 and partly surround the copper plates so that when the three insulating members 33, 34, and 35 are assembled between the composite copper and iron plates they form a passage 80 35 between the adjacent plates for directly ventilating each of the short arcs, the ventilating passage having a lateral width equal to the distance between the insulating members 34 and 35.

40 Since the insulating member 33 completely covers the iron plates, on one side of the ventilating passage 80, the short arcs are prevented from leaving the copper plates, while the hot gases are permitted to vent directly 45 to atmosphere through the vents 80.

Disposed on opposite sides of the stack of the composite copper and iron plates are coils 54 and 70, which set up a radial field flux for causing the short arcs to trace rapidly recurrent paths between the copper conducting 50 plates. The outer end of the coil 54 (see Fig. 5) is connected to the upper end of the arc terminal member 50 which constitutes a support for the contact member 52 on which one end 55 of the arc plays as it is moved through the converging slot into the spaces between the copper conducting plates. Disposed immediately above the arcing contact 52, and attached to the arc terminal 50, is an arc 60 resisting contact 53, preferably made of a silver-tungsten mixture for preventing the arc from injuring and burning the arc terminal 50.

The inner end 57 of the convolute coil 54 65 is bent to the left (see Figs. 2 and 5), so that

it may be connected to the adjacently disposed copper conducting plates 27. The inner end 57 and the outer end of the coil 54 may be connected, respectively, to the adjacently disposed copper conducting plate 27 70 and to the upper end of the arc terminal 50 by any well known manner, such as by silver solder. After the inner end of the coil 54 is soldered or connected to the adjacently disposed copper plate 27, a split insulating 75 washer 55 is disposed therebetween for the purpose of preventing short circuiting of the turns of convolute coil 54. As shown in Fig. 5, that part of the central opening of the washer 54 where the inner end of the coil 54 is connected to the adjacently disposed copper plate 27 is cut away so as to fit around the inner end of the said coil. The outer dimension of the split insulating washer 55 is such that it fits snugly within 80 the central opening of one of the sets of insulating plates 33, 34, and 35 that is disposed substantially in the same plane therewith. In other words, the plates 33, 34, and 35, when assembled, surround, and lie in edge-to-edge relation, with the split washer 55. Also, for preventing short circuiting of the 85 turns of the coil 54, a strip of insulating material 58 is wound between each turn thereof. (See Figs. 2 and 5.)

The other convolute coil 70 is substantially the same as the coil 54, except that it is mounted on the opposite side of the stack of plates (see Figs. 2, 4 and 5). The inner end 72 of the coil 70 is bent to the right so that it may be connected by silver soldering to the adjacently disposed copper plate 27. A split washer 74, somewhat similar to the split washer 55, is disposed between the coil 70 and the adjacently disposed copper plate 27 100 in order to prevent short circuiting of the turns of the said coil. Likewise, that portion of the central opening of the split washer 74 where the inner end of the coil 70 is soldered to the adjacently disposed copper plate 27 is 105 cut away so as to fit around the inner end of said coil. Also, the outer dimension of the split washer 74 is such that it fits snugly within the central opening of one of the sets of insulating plates 33, 34 and 35 that is disposed substantially in edge-to-edge relation therewith. A strip of insulating material 71 is wound between adjacent turns of the coil 70 in order to prevent the short 110 circuiting of its respective turns (see Fig. 4).

The outer end of the coil 70 is connected to side plate 22 by means of screws 81 and the threaded openings 73 provided in the outer end of the said coil (see Figs. 1 and 4). The coils 54 and 70, when assembled, are insulated, respectively, from the side plates 21 and 22 by means of the insulating members 76 and 78.

For the purpose of holding the stack of 120

composite copper and iron plates, and the insulating members in their proper relation, a plurality of insulating pins 46, 47, 48, and 49 are provided. The insulating pins, when the structure is assembled, extend through the openings shown in the iron plates and in the insulating members.

The bolt 23 that extends through the central opening of the copper plates, is surrounded by an insulating tube or member 24 which insulates the bolt 23 from the side plates 21 and 22 and the copper conducting plates. A relatively large, thick insulating washer 25 is disposed between the nut 26 and the side plate 22 for distributing the force that holds the plates together and for insuring further insulating protection.

In describing the operation of the deionizing structure, let it be assumed that the arc ing contacts 15 and 53 have just opened, drawing an arc in the converging slot and that, during this part of the cycle, the current is flowing from the power line 10 to the power line 11. Under this condition, the flux produced by the arc itself interlinks the iron plates and, in consequence, draws the arc inwardly through the converging slot, because the said lines of flux assume the path of the least magnetic reluctance. Since the insulating members 33, 34, and 35 provide a direct vent through the stacks of plates, no appreciable gas pressure is established in advance of the arc, and the relatively weak field produced by the arc itself is sufficient to draw the arc through the converging slot and into the spaces between the copper plates.

As the arc is moved through the converging slot, by the force of its own flux interlinking with the iron plates, the potential gradient of the arc becomes sufficient, due to its reduction in cross-section by the narrow apex of the converging slot, that it may be split into short arcs in the spaces between the copper plates. In other words, the density of ionization gradually increases, by the resulting current concentration, to such a degree that the arc current which flows to the copper plates is great enough to cause thermal ionization of the gas adjacent to the cold copper conducting plates.

However, simultaneously with the arc entering the apex of the converging slot provided by the copper plates, a radial field is set-up by the arc current flowing through the convolute coils 54 and 70 which causes the short arcs to move concentrically between the copper plates until they become extinct. As shown in Figs. 1, 2 and 4, the arc current upon leaving the stationary contact member 52 flows through the arc terminal 50, the outer turn of the convolute coil 54 to the inner turn thereof, the copper conducting plates, in the form of a plurality of short arcs, the inner turn of the convolute coil 70 to the outer turn thereof, thence across the end

plate 22 to the terminal lug 82, as indicated by the arrows in Fig. 1, and then out to power line 11. I have indicated generally in Fig. 2, the paths of radial field flux established by the coils 54 and 70 by the broken lines having arrows thereon indicating their direction of flow. As will be observed, the direction of the flux, as it passes between the copper plates, is perpendicular to the current of the short arcs. This relation between the radial field flux and the short arcs produces a tangential force that causes the short arcs to rotate concentrically at a very high velocity between the conducting plates until they become extinct, which usually occurs when the arc current passes through the first zero point, unless there are sufficient ions present to reignite the arc.

The rapid rotation of the short arc prevents any one spot of the copper conducting plates from being heated sufficiently to cause melting thereof. Because of the direct vents 80 provided by my invention for each of the short arcs, the hot gases and the heat generated thereby are ventilated directly to the atmosphere. This ventilating action maintains the conducting plates at a relatively low temperature so that a large current circuit may be successfully interrupted at frequent and continued intervals.

At this point, I wish to again point out that the width of the ventilating passages 80 is substantially the same width as the copper conducting plates. Thus the heat generated by the short arcs is vented out to atmosphere without encountering any substantial resistance. If for any reason the short arcs attempt to pass through the ventilating passages 80, they will immediately be prevented from doing so, because one side of said passage is completely covered by the insulating member 33.

Therefore, I have disclosed a deionizing arc-extinguishing structure that provides a direct vent for each of the short arcs and, at the same time, prevents the said arcs from passing through the said vents.

Since certain changes in my invention may be made without departing from the spirit and scope thereof, it is intended that all matters contained in the foregoing description and shown in the accompanying drawings shall be interpreted as illustrative and not in a limiting sense.

I claim as my invention:

1. In an arc-extinguishing structure, a plurality of non-magnetic conducting plates, a magnetic plate substantially co-planar with, and surrounding, each of the said non-magnetic conducting plates, and insulating means for spacing the said plates, said insulating means being such as to confine the arc on said conducting plate and to provide a passage for ventilating the said plates.

2. In an arc-extinguishing structure, a

- plurality of deionizing members, a magnetic plate substantially co-planar with, and surrounding, each of the said deionizing members, and means for spacing the said members, said spacing means including a sheet of insulating material which is substantially co-extensive with the magnetic plates and which so overlaps the deionizing members that it causes the arc to contact only the deionizing members. 5
3. In an arc-extinguishing structure, a plurality of deionizing members having means associated therewith for impelling the arc to contact the deionizing members, and means for spacing the deionizing members, said spacing means including a sheet of insulating material which covers the outer annular portion of each of the deionizing members, except for that portion where the arc initially contacts the deionizing plates, and including means for spacing said insulating sheets from one of the adjacent deionizing members. 10
4. In an arc-extinguishing structure, a plurality of members disposed substantially perpendicular to the arc for sub-dividing the arc into a plurality of short arcs, means for spacing the members, and means disposed between the spaced members for providing a substantially annular confined space for the short arcs to move, said means having a thickness less than the width of the space between the members in order to provide a passage for ventilating the arc. 15
5. In a circuit breaker, a plurality of spaced members disposed substantially perpendicular to the arc for sub-dividing the arc into a plurality of short arcs, and insulating means for spacing the said members and for providing a substantially annular confined space for the short arcs to move, said insulating means having portions removed to provide a passage for admitting the arc to contact initially the spaced members and for emitting the hot gases from the spaced members, one side of that part of the passage through which the hot gases pass being provided with a portion of said insulating means in order to prevent the arc from leaving the said annular space. 20
6. In a circuit breaker, a plurality of spaced members disposed substantially perpendicular to the arc for sub-dividing the arc into a plurality of short arcs, and means for spacing the said members in such manner as to provide a passage having an exit portion allowing the escape of gas for ventilating the said members, the exit portion of said passage having one side thereof covered with an insulating material in order to prevent the arc from passing through the entire length of the passage. 25
7. In an arc-extinguishing structure, a plurality of conducting members disposed substantially perpendicular to the arc for the sub-dividing the arc into a plurality of short arcs, a magnetic member substantially co-planar with, and surrounding each of the said conducting members, the said conducting and magnetic members being so shaped as to provide a converging slot for directing the arc to, and concentrating it at, the apex of the slot where it is sub-divided into a plurality of short arcs and transferred between the said conducting members, means for maintaining the short arcs in continuous motion until they become extinct, and means for spacing the said conducting and magnetic members in such manner as to provide a passage having an exit portion allowing the escape of gas for ventilating the said members, the exit portion of the said passage having one side thereof covered with an insulating material in order to prevent the arc from passing through the entire length of the passage. 30
8. In an arc-extinguishing device, a plurality of conducting members for sub-dividing the arc into a plurality of short arcs, and insulating members for spacing the said conducting members, said insulating members being so formed as to provide a passage having an exit portion allowing the escape of gas for ventilating the said members, the exit portion of the said passage being provided with insulating means in order to prevent the arc from passing through the entire length of the passage. 35
9. In an arc-extinguishing device, a plurality of conducting members for sub-dividing the arc into a plurality of short arcs, means for spacing the said members, the conducting and the spacing members being so formed as to provide a passage between the spaced conducting members extending from one edge thereof to another edge thereof, and means for so insulating the passage at one edge of said conducting members that the arc is prevented from passing through the entire length of the passage. 40
10. In an arc-extinguishing device, a plurality of conducting members for sub-dividing the arc into a plurality of short arcs, said conducting members having a radial slot to prevent the induction of eddy currents, a magnetic member substantially co-planar with, and surrounding each of the said conducting members, the said conducting and magnetic members being so shaped as to provide a converging slot for directing the arc to, and concentrating it at, the apex of the slot where it is sub-divided into a plurality of short arcs and transferred between the said conducting members, means for maintaining the short arcs in continuous motion until they become extinct, insulating barriers disposed adjacent to the curved edges of the converging slot in order to protect the edges thereof from the heat of the arc and means for spacing the said conducting and magnetic members in such manner as to provide a passage having an exit portion allowing the escape of gas for ventilating the said members, the exit portion of the said passage having one side thereof covered with an insulating material in order to prevent the arc from passing through the entire length of the passage. 45
11. In an arc-extinguishing device, a plurality of conducting members for sub-dividing the arc into a plurality of short arcs, a magnetic member substantially co-planar with, and surrounding each of the said conducting members, the said conducting and magnetic members being so shaped as to provide a converging slot for directing the arc to, and concentrating it at, the apex of the slot where it is sub-divided into a plurality of short arcs and transferred between the said conducting members, means for maintaining the short arcs in continuous motion until they become extinct, insulating barriers disposed adjacent to the curved edges of the converging slot in order to protect the edges thereof from the heat of the arc and means for spacing the said conducting and magnetic members in such manner as to provide a passage having an exit portion allowing the escape of gas for ventilating the said members, the exit portion of the said passage having one side thereof covered with an insulating material in order to prevent the arc from passing through the entire length of the passage. 50
12. In an arc-extinguishing device, a plurality of conducting members for sub-dividing the arc into a plurality of short arcs, a magnetic member substantially co-planar with, and surrounding each of the said conducting members, the said conducting and magnetic members being so shaped as to provide a converging slot for directing the arc to, and concentrating it at, the apex of the slot where it is sub-divided into a plurality of short arcs and transferred between the said conducting members, means for maintaining the short arcs in continuous motion until they become extinct, insulating barriers disposed adjacent to the curved edges of the converging slot in order to protect the edges thereof from the heat of the arc and means for spacing the said conducting and magnetic members in such manner as to provide a passage having an exit portion allowing the escape of gas for ventilating the said members, the exit portion of the said passage having one side thereof covered with an insulating material in order to prevent the arc from passing through the entire length of the passage. 55
13. In an arc-extinguishing device, a plurality of conducting members for sub-dividing the arc into a plurality of short arcs, a magnetic member substantially co-planar with, and surrounding each of the said conducting members, the said conducting and magnetic members being so shaped as to provide a converging slot for directing the arc to, and concentrating it at, the apex of the slot where it is sub-divided into a plurality of short arcs and transferred between the said conducting members, means for maintaining the short arcs in continuous motion until they become extinct, insulating barriers disposed adjacent to the curved edges of the converging slot in order to protect the edges thereof from the heat of the arc and means for spacing the said conducting and magnetic members in such manner as to provide a passage having an exit portion allowing the escape of gas for ventilating the said members, the exit portion of the said passage having one side thereof covered with an insulating material in order to prevent the arc from passing through the entire length of the passage. 60
14. In an arc-extinguishing device, a plurality of conducting members for sub-dividing the arc into a plurality of short arcs, a magnetic member substantially co-planar with, and surrounding each of the said conducting members, the said conducting and magnetic members being so shaped as to provide a converging slot for directing the arc to, and concentrating it at, the apex of the slot where it is sub-divided into a plurality of short arcs and transferred between the said conducting members, means for maintaining the short arcs in continuous motion until they become extinct, insulating barriers disposed adjacent to the curved edges of the converging slot in order to protect the edges thereof from the heat of the arc and means for spacing the said conducting and magnetic members in such manner as to provide a passage having an exit portion allowing the escape of gas for ventilating the said members, the exit portion of the said passage having one side thereof covered with an insulating material in order to prevent the arc from passing through the entire length of the passage. 65

magnetic members, the spacing means being so formed as to provide a passage open at opposite ends for ventilating the said conducting and magnetic members, and means 5 for so insulating one end of the passage that the arc is prevented from passing through the entire length of the passage.

11. In an arc extinguishing structure, a plurality of conducting members disposed 10 substantially perpendicular to the arc for sub-dividing the arc into a plurality of short arcs, a magnetic member substantially co-planar with, and surrounding, each of the said conducting members, a sheet of insulating 15 material that is substantially coextensive with the magnetic plates, disposed therebetween and so overlapping the outward angular portion of the conducting member that it prevents the short arcs from leaving the 20 said conducting members as they are maintained in continuous motion, means associated with said sheet for spacing said conducting and magnetic members, said spacing means being so formed that it provides 25 a passage for ventilating the conducting and magnetic members, and means for maintaining the arc in continuous motion until the short arcs become extinct.

12. In an arc-extinguishing structure, a 30 plurality of conducting plates for sub-dividing the arc into a plurality of short arcs, means for so spacing the said plates as to provide a passage for ventilating each short arc and means covering the portion of the 35 conducting plates at said ventilating passage to prevent the short arcs from leaving the conducting plates.

13. In an arc-extinguishing structure, a 40 plurality of conducting plates for sub-dividing the arc into a plurality of short arcs, means for so spacing the said plates as to provide a passage for ventilating the short arcs, said passage having a lateral width substantially the same as the width of the 45 conducting plates.

14. In an arc-extinguishing structure, a plurality of spaced deionizing members disposed substantially perpendicular to the arc for sub-dividing the arc into a plurality of 50 short arcs, a plurality of magnetic plates associated with the deionizing members, means for spacing the deionizing members and the magnetic plates, the said magnetic plates being so shaped that when they are assembled they provide a converging entrance slot for directing the arc in between the deionizing members, and insulating barriers disposed along the sides of the converging slot for preventing the arc from contacting the 55 magnetic plates.

15. An arc-extinguishing structure comprising, in combination, a plurality of spaced deionizing members disposed substantially perpendicular to the arc for sub-dividing the 60 arc into a plurality of short arcs, means for

spacing the deionizing members, means including the converging edges of a plurality of plates for directing the arc in between the deionizing members, and a barrier positioned along the edges of said plates for preventing 70 the arc from contacting therewith.

16. In an arc extinguishing structure, a plurality of members of conducting material positioned substantially perpendicular to the arc path for sub-dividing the arc into a plurality of short arcs, means positioned between said members comprising sheets of insulating material, each of which has a centrally disposed opening through which the arc may play between said members of conducting material and only one slot connecting said opening with one edge of said sheet, and means at the edge portions of said sheets of insulating material for providing ventilating 80 passages through said arc extinguisher. 85

17. In an arc extinguishing structure, a plurality of members of conducting material positioned substantially perpendicular to the arc path for subdividing the arc into a plurality of short arcs, and means positioned between said members comprising sheets of insulating material, each of said sheets of insulating material having a body portion of less thickness than at least one of the edge 90 portions, the differing thickness of said portions providing ventilating passages between 95 said members.

In testimony whereof, I have hereunto subscribed my name this 5th day of February, 1932.

WALTER M. AUSTIN.
